Primary Examiner — Shannon W Morgan*Assistant Examiner* — Aula Soroush(74) *Attorney, Agent, or Firm* — Fred Zollinger(57) **CLAIM**

The ornamental design for a ball as shown and described.

DESCRIPTION

FIG. 1 is a perspective view of a ball showing our new design.

FIG. 2 is a front elevation view of thereof.

FIG. 3 is a rear elevation view thereof.

FIG. 4 is a top plan view thereof.

FIG. 5 is a bottom plan view thereof.

FIG. 6 is a left side elevation view thereof; and,

FIG. 7 is a right side elevation view thereof.

The dashed lines shown in the drawings are for purposes of illustrating portions of the ball that form no part of the claimed design.
